(No Model.)

F. CHALLONER.

SPALT DROPPING MECHANISM FOR SHINGLE SAWING MACHINES.

No. 442,171.

Patented Dec. 9, 1890.

UNITED STATES PATENT OFFICE.

FRANK CHALLONER, OF OSHKOSH, WISCONSIN.

SPALT-DROPPING MECHANISM FOR SHINGLE-SAWING MACHINES.

SPECIFICATION forming part of Letters Patent No. 442,171, dated December 9, 1890.

Application filed July 21, 1890. Serial No. 359,469. (No model.)

To all whom it may concern:

Be it known that I, FRANK CHALLONER, of Oshkosh, in the county of Winnebago and State of Wisconsin, have invented certain new and useful Improvements in Spalt-Dropping Mechanism for Shingle-Sawing Machines; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

15 My invention relates to that class of shingle-sawing machines which employ a rotary carriage provided with a number of receptacles or openings for shingle-bolts. Its main object is to discharge the "spalts," when desired, from the several receptacles of the carriage, and in accomplishing that object to dispense with the circular supporting way or ways and movable track-sections heretofore employed in this class of machines.

25 It consists, essentially, of suitable dog releasing or operating mechanism and a pin or trip on the carriage for each receptacle movable into abnormal position, so as to set said mechanism in motion, and thereby open the dog and release the spalt in the adjacent receptacle at the proper point to discharge it from the carriage.

In the accompanying drawings like letters designate the same parts in the several figures.

35 Figure 1 is a plan view of a portion of the carriage in connection with my improved spalt-dropping mechanism. Fig. 2 is a radial vertical section of a portion of the carriage, showing the spalt-dropping mechanism in elevation. Fig. 3 is a section of the carriage at right angles to that shown in Fig. 2, and shows the spalt-dropping mechanism, looking toward the center of the machine; and Fig. 4 is a sectional detail on an enlarged scale, showing one of the trip-pins of the carriage and a device for holding it in place.

45 *l* represents a portion of a rotary carriage of a shingle-sawing machine, and *c*² the outer movable dog of one of the shingle-bolt receptacles, all of the usual or any suitable con-

struction. The outer or movable dogs have central arms on the outside provided with downwardly-projecting crank-pins *c*', upon which are journaled friction-rollers *c*. At the 55 proper point for discharging spalts a curved bar *a* is supported normally just inside of the path of the rollers *c* by standards *b* *b*, which are fixed at their lower ends to a horizontal rock-shaft *d*, held in suitable bearings (not shown) transversely to the diameter of the machine, cutting it through the middle. Upon the shaft *d* is fixed a horizontally-projecting arm *b*', provided at the end with a friction-roller *b*².

65 *h* is a horizontal shaft placed a little below and transversely to the shaft *d*. It has a suitable driving connection, (not shown,) by which it is continuously driven when the machine is in operation in the direction indicated by the 70 arrow, Fig. 3, and is supported in suitable fixed bearings. (Not shown.) Upon the shaft *h* is loosely mounted a cam *g*, bearing at its periphery against the friction-roller *b*² of arm *b*' and provided with clutch formations or projections *t*' *t*' on its outer face. It is restrained from endwise movement by collars or shoulders on the shaft *h*. A head *g*² is fixed upon the shaft *h* near the outer side of cam *g*, and is formed with recesses, in which are inserted 80 dogs formed on the inner ends of longitudinally-movable rods *t* *t*. These rods *t* *t* are inserted in longitudinal grooves in shaft *h*, extend through and are held in place by a box *g*³, and are bent outwardly at their outer ends, 85 as shown in Fig. 1, each rod being movable independently of the other into and out of engagement with the projections *t*' *t*' on cam *g*.

90 *c*² is an upright shaft supported in suitable bearings and provided at its upper end with an arm *e*, having a horizontal incline at the end, and near the lower end with a similar arm *e*³, having a vertical incline at the end, which is movable by the turning of said shaft *e*² inwardly into the path of rotation of the 95 outer ends of the rods *t* *t*.

95 *e*⁴ is an incline attached to the outer end of the box *g*³ opposite the incline on arm *e*³, so as to engage with the overhanging ends of rods *t* *t* and withdraw them from engagement with the projections *t*' *t*' on cam *g*.

100 Adjacent to each bolt-receptacle the car-

riage is provided with a vertically-movable pin e' , which may be depressed by the operator into range with the incline of arm e .

- p represents a vertical incline suitably supported in the path of the pins e' and arranged to return the same to their normal positions after they have been depressed and have acted upon the incline of arm e . The pins e' are held in place when raised out of range 10 with arm e by the device shown in Fig. 4, which consists of a frictional bearing-piece n , inserted and movable longitudinally in a horizontal socket in the carriage l and held by a spring o with an elastic pressure against 15 the side of the pin e' . The spring o bears at the inner end against a head or shoulder on the bearing-piece n and at its outer end against a plug m , screwed into the said socket. The arm e^3 is held normally out of range with 20 the outer ends of the rods t by a spring k , (clearly shown in Fig. 3,) and the dog c^3 is forced and held normally in engagement with a shingle-bolt by the usual springs or any suitable device. (Not shown.)
- 25 The mechanism hereinbefore described may with slight modification be applied to the inner dogs, and may be otherwise variously modified in its details and arrangement without affecting its mode of operation or departing from the spirit of my invention.

My improved device operates as follows: When it is desired to discharge a spalt from any receptacle in the carriage, the operator depresses the pin e' adjacent to the receptacle. The pin thus depressed engages with the incline of arm e and swings it with the arm e^3 inwardly. The latter, engaging with one of the rods t as it passes, forces it into engagement with a projection t' on cam g and 30 causes the cam to make a half-revolution with the shaft h , when the outwardly-bent end of the rod t , riding upon the fixed incline e^4 , is withdrawn from engagement with the projection t' , allowing the cam g to come to rest. 40 While the cam g is thus making a partial revolution the friction-roller b^2 rides over one of the enlarged portions of the cam, and the arm b' is raised and the standards b and curved bar a at their upper ends are swung 45 outwardly during the interval that the friction-roller c is passing outside of said bar. The dog c^3 is thereby forced outwardly, so as to release the spalt and allow it to fall out of the carriage. After the pin e' passes the 50 arm e it rides over the fixed incline p and is raised into normal position, in which it is held by the spring-actuated bearing-piece n until it is again depressed by the operator.

The shaft h is geared to make one revolution while the carriage turns the distance of one bolt-receptacle, so that, if desired, the spalts or bolts may be dropped in succession from all the receptacles of the carriage during a single revolution thereof.

65 I claim—

1. In a shingle-sawing machine, the combination of the carriage provided with a mov-

able dog and a trip movable into abnormal position, mechanism arranged to shift the dog at the proper point for discharging a spalt, 70 and a movable part with which said trip engages when in abnormal position, having a connection with the dog-shifting mechanism, so as to set the same in motion, substantially as and for the purposes set forth. 75

2. In a shingle-sawing machine, the combination of a rotary carriage having a number of bolt-receptacles, each provided with a movable dog, mechanism arranged to shift said dogs at the proper point in the rotation of 80 the carriage for dropping spalts, a movable part connected with and arranged to set said mechanism in operation, and a trip for each bolt-receptacle of the carriage moving therewith and movable into abnormal position, in 85 which it is arranged to engage with said movable part and set the dog-shifting mechanism in motion, substantially as and for the purposes set forth.

3. In a shingle-sawing machine, the combination of a rotary carriage having a number of bolt-receptacles, each provided with a movable dog and having a trip for each receptacle movable into abnormal position, dog-shifting mechanism, a movable part connected 95 with the dog-shifting mechanism and arranged to be engaged by said trips when the latter are in abnormal position, and a device arranged to automatically return said trips to their normal positions after they have acted 100 on said movable part, substantially as and for the purposes set forth.

4. In a shingle-sawing machine, the combination of a rotary carriage having a number of bolt-receptacles, each provided with a movable dog, a laterally-movable bar arranged to engage with projections on the dogs and to shift the same at the proper point for discharging spalts, mechanism connected with and arranged to move said bar laterally, 105 a movable part connected with said shifting mechanism for setting the same in motion, and trips on the carriage—one for each bolt-receptacle—movable into abnormal position, so as to engage with said movable part and 110 start the shifting mechanism, substantially as and for the purposes set forth.

5. In a shingle-sawing machine, the combination of a rotary carriage having a number of bolt-receptacles, each provided with a movable dog, a laterally-movable bar arranged to engage with projections on the dogs and shift the same as they pass, a shaft continuously rotated while the machine is in operation, a cam loosely mounted upon said shaft and having suitable connections with said bar, and a clutch for throwing said cam into and out of gear, substantially as and for the purposes set forth. 120

6. In a shingle-sawing machine, the combination of a rotary carriage having a number of bolt-receptacles, each provided with a dog and a trip movable into abnormal position, mechanism for shifting the dogs at the proper 130

point for discharging spalts, a cam arranged to actuate said mechanism, and a movable part in range of said trips when they are in abnormal position having suitable connections by which the actuating-cam is set in motion, substantially as and for the purposes set forth.

7. In a shingle-sawing machine, the combination of a rotary carriage having a number of bolt-receptacles, each provided with a movable dog, dog-shifting mechanism, a cam arranged to actuate said mechanism, a driving-shaft upon which the cam is loosely mounted, provided with a dog movable into engagement with said cam, a rock-shaft having an arm arranged to engage said dog and move it into engagement with the cam, trips on the carriage movable into abnormal position in which they engage a projection on said rock-shaft, and an incline for withdrawing said dog from engagement with the cam, substantially as and for the purposes set forth.

8. In a shingle-sawing machine, the combination of the carriage provided with a trip-pin or its equivalent movable into abnormal position, mechanism for shifting an adjunctive part of the machine arranged to be set in motion by said trip-pin when it is in abnormal position, and a spring-actuated frictional

bearing-piece for holding said trip-pin in its 30 normal position, substantially as and for the purposes set forth.

9. In a shingle-sawing machine, the combination, with the carriage having shingle-bolt receptacles provided with movable dogs, of 35 mechanism arranged to open said dogs automatically at the proper point and time for discharging spalts, and means under the control of the operator of setting said mechanism in motion, substantially as and for the purposes set forth.

10. In a shingle-sawing machine, the combination, with the carriage having shingle-bolt receptacles provided with movable dogs, of 45 mechanism arranged to open said dogs at the proper point and time for discharging spalts, and trips on the carriage by which the dog-shifting mechanism is set in motion at the will of the operator to discharge a spalt from either bolt-receptacle, substantially as and 50 for the purposes set forth.

In testimony that I claim the foregoing as my own I affix my signature in presence of two witnesses.

FRANK CHALLONER.
